UNSEATING STRUCTURE FOR ROTARY
PLUG VALVES

Lucien W. Mueller and Frederick Tratzik, Decatur, Ill., assignors to Mueller Co., Decatur, Ill., a corporation of Illinois

Application October 31, 1946, Serial No. 706,904

11 Claims. (Cl. 251—91)

1

The present invention relates to valves.

An object of the invention is to provide a rotary valve including means to enable the plug to be tilted or canted radially with respect to its seat so that it can readily be operated.

Other objects and advantages of the invention will be apparent from the following specification and the accompanying drawings wherein:

Figure 1 is an axial section through a valve.

Figure 2 is a transverse section on the line 2—2 of Figure 1.

Figure 3 is a transverse section on the line 3—3 of Figure 1.

Figure 4 is a detailed axial section with the plug in intermediate position.

Figure 5 is an axial section of a modified valve showing the plug in opened position, and

Figure 6 is an axial section of the valve showing the lower portion of the Figure 5 structure, but with the plug in closed position.

Referring to Figures 1 to 4, the numeral 10 designates the valve body element or casing which is provided with a seat bore 11 and a flow passageway 12 including an inlet port 12a and an outlet port 12b. One end of the seat bore is closed, for example, by the imperforate wall indicated at 13. The opposite end of the seat bore is adapted to be closed by a plate 14 secured to the body element 10 by bolts 15, so that the plate element is removable. Plate 14 includes a central aperture 14a surrounded by a boss 14b.

The valve element or plug is designated by the numeral 16 and includes a flow port 16a. In the illustrated embodiment of the invention, the valve element is covered with a resilient material 17. However, the use of a resilient covering on the plug may be eliminated without departing from the present invention.

One end of the valve element 16 has a stem 18 projecting therefrom and stem 18 extends into an operating element or sleeve 19 of cup-like form. In more detail, the extreme outer end of stem 18 is square in cross section to provide a plurality of flat faces 20 which loosely engage opposed flat faces 21 on the interior of the opposite portion of the operating sleeve 19. Inwardly of the above-mentioned flat faces, the stem 18 is circular in cross section, as indicated at 22 in Figure 3. The inner portion of the plug stem is rounded to have a journal fit with an opposed circular surface of sleeve 19. At its inner end, sleeve 19 is provided with a radial flange 24 and at least the outer surface of this flange is ground and adapted to bear upon an opposed ground sur-

2

face of plate 14 so that friction will be reduced over these areas.

In order to exert axial pressure on plug 16, a hardened steel ball 25 is pressed against the outer wall of the sleeve 19 by a coil spring, as shown in Figure 1. In more detail, the coil spring is mounted in a pocket in the extreme outer end of stem 18, so that plug 16 will be held in bearing contact with the opposite end of body element 10, but with sufficient freedom of movement to permit a slight tilting action, as will be hereinafter described.

In order to provide a seal between the element 19 and the wall of bore 14a of plate 14, element 19 may be provided with a sealing element of the O-ring type designated by the numeral 26, and which is mounted in a circumferential groove in element 19. O-ring 26 is normally round in radial section but will be spread to be elliptical in radial section by pressure moving along sleeve 19. Thus, even when sleeve 19 is canted as hereinafter described, ring 26 will firmly engage the wall of aperture 14a and the inner surface of the groove in which the ring is mounted.

It is found that when rotary valves are used to control high pressure flow, the action of the fluid urges the plug element against the mouth of the outlet port 12b, thereby increasing the difficulty of operating the plug. If the plug is of a rubber covered type, it may be moved toward the outlet port to such a degree that the rubber covering of the plug will project into the outlet port and be scored or otherwise marred when the plug is moved to open position. For example, if the plug is in the closed position illustrated in Figure 1, the pressure of line fluid acting through inlet passage 12a may force the plug to the right with respect to Figure 1 to such an extent as to render it difficult to rotate the plug to open position because the rubber covering 17 will project slightly into the mouth of the outlet passage 12b.

In order to enable the plug to be operated more readily, the outwardly projecting flange or boss 14b of plate 14 is provided with a radial aperture 30 in which a hardened steel ball 31 is mounted, the ball being held in proper position by means of a set screw 32 locked in adjusted position by a smaller set screw, as shown in Figure 1. Ball 31 is adapted to engage a groove 33 which extends circumferentially of the outer surface of sleeve 19. A pocket 34 of slightly greater radial depth than groove 33 is provided at one end of the groove and a similar pocket 35 is provided at the opposite end of the groove. The pockets are

preferably spaced by 90°, i. e., the arc of rotation of the plug 16 between open and closed position.

The end of the plug 16 adjacent the closed end 13 of the casing will have a metal bearing plate 38 secured thereto and a similar plate 39 will be secured in the opposed inner surface of the casing. A hardened steel ball 40 will be positioned between the two plates, thereby providing a bearing surface which will permit the plug to be rotated even while canted. The spring-pressed ball 25 will urge the plug into contact with ball 40.

In the use of the valve of Figures 1 to 4, with the plug in the closed position of Figure 1, the pressure acting through the inlet port 12a may tilt the valve on ball 40 so that the plug will lean very slightly to the right, as viewed in Figure 1. As has been explained above, this canted position of the plug may cause its rubber covering to project into the outlet port 12b. Even if the plug is not covered with a resilient element, it will be more difficult to operate by reason of the canting resulting from the pressure acting through the inlet port 12a.

As is indicated in Figure 1, the outer diameter of the operating or sleeve element 19 is sufficiently smaller than the diameter of the aperture 14a in plate 14 as to permit the above-described canting of the plug. Also, when the valve is in the closed position indicated in Figures 1 and 3, there will be sufficient play between ball 31 and pocket 34 as to permit the plug to be canted or "float" so as to obtain a highly efficient seal against the outlet passage.

When it is desired to move the valve from closed position to open position, a wrench will be applied to the operating element or sleeve 19 so as to rotate that element in a counter-clockwise direction, as viewed in Figure 3. During initial rotation of element 19, the loose fit between the flat surfaces 20 and 21 will permit element 19 to rotate slightly with respect to the plug stem so that the surface of the groove 33 will move beneath the ball 31. This will force the element 19 to the left, as viewed in Figure 1, and the journal fit between the round portion of plug stem 18 and the round bore in element 19 will cause the plug to be correspondingly tilted so as to cant it away from the outlet port. When the rotational play between the flat surfaces 20 and 21 has been taken up, the plug 16 will rotate with the stem, the plug being canted as just described. However, when movement of the plug to open position is completed, the pocket 35 will move opposite ball 31 so that the element 19 and the plug will again be free to float. Movement of the plug from open to closed position will be the reverse of the action just described.

Because of the fact that the round portion of plug stem 18 has a close fit with the round surface portion of operating element 19, the canting movement of the operating element 19 will be exactly conformed to by the plug. As has been indicated above, O-ring 26 will prevent leakage between the plate 14 and the operating element 19.

Referring to Figures 5 and 6, the structure disclosed therein is identical with that of Figures 1 to 4 except that the plug 16' of Figures 5 and 6 has recesses 59 therein so that its closely fitting resilient covering 17' will include corresponding recesses 60. The recesses 60 have the same outline as the inlet and outlet ports 61 and 62 of flow passageway 12' and are positioned on a line extending 90° with respect to the flow port 63 of the plug.

As is shown in Figure 6, the provision of the recesses 60 will obviate the possibility of the resilient

covering being projected into the outlet passage 62 when the plug is in closed position. Because there will be less material within the area defined by the mouth of the outlet passage 62 when the plug is in closed position, the covering cannot be forced into the outlet mouth by any canting action of the plug, such as will result from the pressure acting through the passage 61. The principal reason for providing two recesses 60 is to enable the plug to be rotated in either direction. However, it will be understood that stops will ordinarily be provided upon the valve to limit any given installation to a 90° rotation.

It will be apparent that the recess arrangement disclosed in Figures 5 and 6 may be used in a valve which does not include the canting arrangement of Figures 1 to 4.

The terminology used in the specification is for the purpose of description and not of limitation, the scope of the invention being defined in the claims.

We claim:

1. In a valve, a valve casing including a seat bore and a flow passage extending transversely of the seat bore, a ported plug rotatable in the seat bore, a pivot bearing between one end of said ported plug and the opposed surface of said valve casing, and co-acting means carried by the opposite end of the plug and the opposed surface of the valve casing to tilt the plug with respect to the seat bore during rotation of the plug.

2. In a valve, a valve casing including a seat bore and a flow passage extending transversely of the seat bore, a ported plug rotatable in the seat bore, a pivot bearing between one end of said ported plug and the opposed surface of said valve casing, and co-acting means carried by the opposite end of the plug and the opposed surface of the valve casing to tilt the plug with respect to the seat bore during rotation of the plug, said co-acting means acting radially of the plug and seat bore.

3. In a valve, a valve casing including a seat bore and a flow passage extending transversely of the seat bore, a ported plug rotatable in the seat bore, a pivot bearing between one end of said ported plug and the opposed surface of said valve casing, an operating stem on the other end of said plug, an aperture at one end of the seat bore through which the plug operating stem extends, and co-acting means positioned between the operating stem and the opposed surface of the aperture to tilt the plug with respect to the seat bore during rotation of the plug.

4. In a valve, a valve casing including a seat bore and a flow passage extending transversely of the seat bore, a ported plug rotatable in the seat bore, a pivot bearing between one end of said ported plug and the opposed surface of said valve casing, and co-acting means carried by the opposite end of the plug and the opposed surface of the valve casing, said co-acting means including a pocket and a radial projection adapted to seat in said pocket in a limit position of said plug and to tilt said plug when unseated.

5. In a valve, a valve casing including a seat bore and a flow passage extending transversely of the seat bore, a ported plug rotatable in the seat bore, a pivot bearing between one end of said ported plug and the opposed surface of said valve casing, co-acting means carried by the opposite end of the plug and the opposed surface of the valve casing, said co-acting means including pockets circumferentially spaced by a distance substantially corresponding to the arc of rotational movement of the plug between open

and closed position of the latter and a radial projection adapted to seat in the respective pockets in open and closed position of said plug and to tilt said plug when in an intermediate position.

6. In a valve, a valve casing including a seat bore and a flow passage extending transversely of the seat bore, a ported plug rotatable in the seat bore, a pivot bearing between one end of said ported plug and the opposed surface of said valve casing, co-acting means carried by the opposite end of the plug and the opposed surface of the valve casing, said co-acting means including a circumferentially extending groove with pockets at the respective ends of said groove and a radial projection adapted to seat in the respective pockets in open and closed positions of the plug and to cooperate with said groove in the intermediate position of rotation of the plug to tilt the plug with respect to the seat bore.

7. In a valve, a valve casing element including a seat bore and a flow passage extending transversely of the seat bore, a ported plug element rotatable in the seat bore, a plate closing one end of the seat bore, said plate having a central aperture therein, a sleeve element rotatable in and spaced from the plate aperture, the plug being provided with an operating stem projecting into the sleeve element, the stem and the sleeve element respectively being provided with abutting surfaces substantially parallel to the plug element axis, said sleeve element having a circumferentially extending groove therein with a pocket at each end of the groove, a ball mounted in the surface of the plate aperture adapted to seat in the respective pockets in open and closed positions of the plug element, and a pivot bearing between the end of the plug opposite from its stem and the opposed surface of the valve body element.

8. In a valve, a valve casing element including a seat bore and a flow passage extending transversely of the seat bore, a ported plug element rotatable in the seat bore, a plate closing one end of the seat bore, said plate having a central aperture therein, a sleeve element rotatable in and spaced from the plate aperture, the plug being provided with an operating stem projecting into the sleeve element, the stem and the sleeve element respectively being provided with opposed flat surfaces substantially parallel to the plug element axis and sufficiently spaced to enable the sleeve element to rotate slightly relatively to the plug stem, the plug stem also including an inner peripheral circular surface which closely contacts with a corresponding surface of the sleeve element so that the sleeve element and plug may be canted together, said sleeve element having a circumferentially extending groove therein with a pocket at each end of the groove, a ball mounted in the surface of the plate aperture adapted to seat in the respective pockets in open and closed positions of the plug element, and a pivot bearing between the end of the plug

opposite from its stem and the opposed surface of the valve body element.

9. In a valve, a valve casing including a seat bore and a flow passage extending transversely of the seat bore, a ported plug rotatable in the seat bore, a pivot bearing between one end of said ported plug and the opposed surface of said valve casing, one of the seating surfaces of the valve being resilient, and co-acting means carried by one end of the plug and the opposed surface of the valve casing to tilt the plug with respect to the seat bore during rotation of the plug.

10. In a valve, a valve casing including a seat bore and a flow passage extending transversely of the seat bore, a ported plug rotatable in the seat bore, a pivot bearing between one end of said ported plug and the opposed surface of the said valve casing, an operating stem on said plug, said valve casing having an aperture at one end of the said bore and through which the plug operating stem extends, means rotatable with said operating stem and defining a groove extending circumferentially of the operating stem and including pockets at the respective ends of the groove, and a ball element rigidly mounted in the wall of said aperture and adapted to seat in the groove pockets when the plug is in limit positions and to cooperate with said groove in the intermediate positions whereby said ported plug is tilted with respect to said seat bore.

11. In a valve, a valve casing including a seat bore and a flow passage extending transversely of the seat bore, a ported plug rotatable in the seat bore, a pivot bearing between one end of said ported plug and the opposed surface of said valve casing, coacting means carried by the opposite end of the plug and the opposed surface of the valve casing to tilt the plug with respect to the seat bore during rotation of the plug, said plug being provided with a resilient seating surface which is recessed over an area which will be opposite the casing flow passage in closed position of the plug.
